UNITED STATES PATENT OFFICE.

ALEXANDER N. PIERMAN, OF NEWARK, NEW JERSEY.

COLOR PHOTOGRAPHY.

1,196,718.

Specification of Letters Patent. Patented Aug. 29, 1916.

Application filed April 8, 1908. Serial No. 425,854.

To all whom it may concern:

Be it known that I, ALEXANDER N. PIERMAN, a citizen of the United States, and a resident of Newark, in the county of Essex and State of New Jersey, have invented certain new and useful Improvements in Color Photography, of which the following is a description.

My invention relates to improvements in the art of color photography and particularly to an improved plate or film for utilization in this art.

My invention also comprises a novel process for making plates or films for color photography, and it also comprises the provision of a novel film for use in color photography wherein the usual transparent base may be dispensed with, and a process for making the same.

Other objects of my invention will be pointed out in this specification and subsequently claimed.

The color screen of which I will make use in forming my improved plate or film is preferably made in the following manner: Having first provided a quantity of material which may be woven and which can be obtained in very fine strands, as for example, spun glass or silk, I divide this material into three lots separately colored blue, red and green respectively. If spun glass be used it can be spun from the colored glass and no subsequent coloring is necessary, but silk or like materials must be dyed with the various colors. It is to be understood, of course, that the precise shades of these colors may be varied somewhat, so that the fabric ultimately will appear as near white as possible. I then preferably weave these strands into a sheet, arranging the differently colored strands in rotation, first a blue, then a green, and then a red, and so on, making use of a weft of a fibrous or similar material which is substantially white or colorless. When spun glass is used for the colored elements, weft strands of silk are used as is the ordinary practice in weaving fabrics from this material. The separately colored strands are placed substan-

tially in contact with one another, so that all light which passes through the fabric must traverse some one of these strands and cannot pass between them. I may, of course vary the precise arrangement in weaving from that above described, but whatever arrangement may be chosen it is obvious that such arrangement will be entirely under the control of the weaver. While I regard weaving as the preferable mode for making the screen, I do not wish to be limited to a woven screen as it may be formed in any way in which the relation of its colored elements may be subject to entire control.

In the drawings annexed to this specification and forming a part hereof, the same reference numerals being uniformly used therein to designate the same parts, Figure 1 is a plan view of a color screen, the weft threads being omitted for clearness of illustration; Fig. 2 is a cross-sectional view of a film or plate wherein the color screen is used in connection with a transparent foundation; Fig. 3 is a view similar to Fig. 2 of a film wherein the color screen is embedded in a ribbon, the transparent foundation of the form of film shown in Fig. 2 being omitted, and Fig. 4 is a fragmental detail plan view of the screen on an enormously magnified scale.

The screen 1 is shown diagrammatically in Fig. 1 as being made up of the variously colored strands 2, 3 and 4 arranged in rotation parallel to one another, the weft omitted in this view but being shown at 7 in Fig. 4.

Having formed the color screen as above described, I make use of the same in either of the following ways: I may take a suitable transparent foundation 5, such, for example, as a glass plate or a celluloid film, and secure the color screen 1 thereto by means of a suitable transparent cement or varnish 8. In applying this screen to the foundation in this way, suitable means may be employed for pressing the foundation and screen together, as for example, they may be passed between pressure rollers, or other means for obtaining an intimate contact may be made

use of, as will be understood. The transparent foundation with the screen secured thereto is now thoroughly dried and a coating of sensitized material 6, such for example, as silver bromid emulsion is applied thereto upon the screen in the way in which ordinary photographic plates or films are sensitized. The plate or film thus made, when dried, is ready for use and a color photograph may be formed thereon by exposing it in a camera with the transparent foundation placed on the side toward the lens, the light passing first through this foundation and then traversing the color screen and finally reaching the sensitized film or plate. After exposing, the plate or film is developed in the usual way in the dark, or in a very dull red light at a safe distance, the image appearing as a negative, after which the image, which, when silver bromid is used as the sensitizing agent, is composed of reduced silver, is dissolved out with the proper chemicals, as is well known in the art, leaving the balance of the coating of unexposed silver bromid intact. The plate is then washed and immersed in a second developer and taken from the dark room out into strong daylight to expose the remaining silver bromid, and this second development is completed in the light. After the plate or film is washed and dried, the picture is complete and may be viewed by transmitted light, the same colors appearing in the picture as in the object photographed.

An alternative way in which I may make use of my improved color screen for making color photographs consists in embedding the screen in a flexible ribbon preferably by saturating the fabric which makes up the screen with a collodion or celluloid solution and then thoroughly drying the same. By this means I am enabled to dispense with any transparent foundation such as shown at 5 in Fig. 2 and to provide a substantially integral foundation and color screen, the integral foundation comprising a flexible ribbon, the material of which covers all the strands of the color screen, fills all interstices between the strands and is substantially symmetrically disposed on both sides of the screen as shown in Fig. 3. After a film has been formed in this way, I apply a sensitized coating 6 to either face of the film and expose and develop this film as above described. A film so formed may be made extremely thin and can be made use of for directly printing therefrom a second film precisely similar to the first, this second film being afterward subjected to the usual process of developing and re-exposing and re-developing. This is possible because of the extreme thinness of such a film which makes it possible to secure substantially a

contact print, and because of the variously colored elements of the color screen being entirely under control in their arrangement on the screen, making it possible to so position the film which is being printed from, relative to the film being printed, that the variously colored elements in one may be made to register accurately with the similarly colored elements in the other. By this means I am enabled to make from one exposure an indefinite number of color photographs.

Having now described my invention, I claim:

1. A film for use in color photography, comprising a flexible self-held-together color screen and a flexible, transparent or translucent ribbon in which said screen is embedded, the material of the ribbon being disposed substantially symmetrically on both sides of the screen, and having a coating of sensitized material applied thereto, substantially as described.

2. A film for use in color photography, comprising a flexible self-held-together color screen and a ribbon formed from a collodion solution and in which the said screen is embedded and substantially symmetrically disposed on both sides thereof, and having a coating of sensitized material applied thereto, substantially as described.

3. The process of making a film for use in color photography, which consists in forming a self-held-together color screen with the colors arranged in a definite and regular order, in saturating the screen with a suitable solution and disposing the material of the solution substantially symmetrically on both sides of the screen, in drying the screen so treated, and in applying thereto a layer of sensitized material, substantially as set forth.

4. The process of making a film for use in color photography, which consists in forming a flexible color screen by weaving differently colored flexible strands with the colors arranged in a definite and regular order, in saturating the screen with a suitable solution and disposing the material of the solution substantially symmetrically on both sides of the screen, in drying the screen so treated, and in applying thereto a layer of sensitized material, substantially as set forth.

5. A film for use in color photography, comprising a self-held-together color screen consisting only of woven strands, a flexible transparent or translucent ribbon in which said screen is embedded, the material of the ribbon being disposed substantially symmetrically on both sides of the screen, and a coating of sensitized material upon said screen and ribbon, substantially as described.

6. A film for use in color photography,

comprising a flexible transparent or translucent ribbon, a flexible color screen consisting only of woven strands embedded in said ribbon, and a sensitized emulsion applied to the ribbon, the said ribbon and screen forming the sole support for the emulsion, and the material of said ribbon being disposed substantially symmetrically

on both sides of the screen, substantially as described.

This specification signed and witnessed this 24th day of March 1908.

ALEXANDER N. PIERMAN.
